UNITED STATES PATENT OFFICE.

FRIEDRICH W. BAUMGAERTNER, OF CLEVELAND, OHIO, ASSIGNOR TO WINDSOR T. WHITE, TRUSTEE, OF CLEVELAND, OHIO.

VACUUM FEED DEVICE FOR INTERNAL-COMBUSTION ENGINES.

1,192,370.

Specification of Letters Patent.

Patented July 25, 1916.

Application filed May 15, 1915. Serial No. 28,482.

To all whom it may concern:

Be it known that I, FRIEDRICH W. BAUMGAERTNER, a subject of the Emperor of Germany, residing at Cleveland, in the county of Cuyahoga and State of Ohio, have invented a certain new and useful Improvement in Vacuum Feed Devices for Internal-Combustion Engines, of which the following is a full, clear, and exact description.

10 This invention relates to devices which, when connected with some air exhausting device, as for example, the inlet side of an internal combustion engine, and with the carbureter therefor, and with a fuel supply tank located below said carbureter, will automatically draw liquid fuel from the supply tank, and deliver it as required to the carbureter.

20 The objects of the invention are to increase the storage capacity of such devices without increasing their size, to cheapen the cost of such devices, to increase their efficiency, and to render them less liable to get out of order or to break.

25 The invention consists in the construction and combination of parts shown in the drawings and hereinafter described and definitely pointed out in the appended claims.

30 In the drawings, Figure 1 is a central vertical section of a device embodying the invention when the parts are in the position they will occupy when the suction valve is closed; Fig. 2 is a diagrammatic view which 35 shows the device may be connected with the fuel supply tank, the carbureter, and the intake manifold of the motor; Fig. 3 is a sectional view like Fig. 1, except that it shows the position of the parts of the device when 40 the suction valve is open; Fig. 4 is a sectional plan view in the plane indicated by line 4—4 on Fig. 3, and Fig. 5 is a plan view of the device.

45 Referring to the parts by letters, A represents the storage tank which may be of any desired capacity. This must always be open to atmospheric pressure; and to effect this one of the bolts *m* which secures the cover *E* in place may be tubular. This has through 50 its bottom a fuel discharge opening *a*, with which the pipe *c* may be connected, whose other end may be connected with the carbureter *C*. B represents a suction tank adapted to be connected by means of a pipe *P* with 55 the inlet manifold *M* of the motor; and by

means of a pipe *R* with the fuel supply tank. D represents the float chamber. These three parts, A, B and D, are shown as concentrically arranged, one within another; but this arrangement of these parts, while valuable 60 from the manufacturing viewpoint, is not at all essential to their successful co-operation with one another or with the other associated parts. It is essential that the suction tank B shall be capable of discharging 65 into the storage tank, A, through an opening, as the pipe *Q*, having such a valve, as *q*, as will substantially prevent the liquid fuel from flowing in the reverse direction, and which will automatically close and prevent the liquid from flowing out when there is a sufficient degree of vacuum in said suction tank. It is also essential that the float chamber and the suction tank be relatively 70 so located and so connected, that liquid fuel will run from the suction tank into the float chamber in substantially the manner herein-after described, during the filling of said suction tank; and may run out of said float chamber while the suction tank is emptying. 75

In the construction shown, the suction tank B has an outwardly extended flange *b* which extends over the top edge of the storage tank and is clamped down upon the same by the cover *E*, which thereby serves as the 80 top of said storage tank. Preferably a packing ring *b'* is located above said flange *b* and between it and the cover. The suction tank is, therefore, substantially air-tight, except 85 at the times and under the conditions hereinafter described.

The cover *E* and the float chamber *D* are preferably cast in one piece,—and in that event, to get the float *F* into the float chamber, the bottom *d'* of said float chamber must be removable, as shown. There is a bushed hole *d* through the bottom of this float chamber; and the upper end of this hole is in the form of a tapered valve seat adapted for co-operation with the tapered valve *f* on the bottom of the float. The cover *E* is also formed with an inwardly directed centrally disposed tubular member *e* whose lower end is closed by the screw plug *H*. In this screw plug are one or more air holes *h*, and also a 100 centrally disposed hole *h'* through which the valve stem *G* passes and may slide, said valve stem being fixed to and projected upward from the float *F*. The upper end of this tubular member *e* is closed by a screw 105

plug made preferably of two parts J and K, which, when, separately completed, are fitted, friction tight, one within the other. Through the upper end of the part J is an air outlet hole j , which contains near, but preferably not at, its lower end, a tapered valve seat for cooperation with the tapered valve g on the upper end of the valve stem G . The upper end of this hole j is preferably threaded to facilitate the connection thereto of the pipe P , which, as before stated, is also connected at its outer end with the inlet manifold of the motor. There is also in the part K a hole k^3 , which is in alignment with the hole j , and likewise with the hole k' in the plug H. The valve stem G passes through these three holes and may slide in them. The upper end of the valve stem adjacent to the valve seat g rather nicely fits in the lower end of the hole j below the tapered valve seat therein, and it also nicely fits in the hole k^3 in the part K.

In the part J is an air duct j^3 , which communicates at its upper end with an external annular groove j^4 in said part, and at its lower end with a transversely extended air duct k^2 in the part K, which duct also communicates with the hole k^4 . When the float F is up to the position such that the valve g is closed, the interior of the suction tank will be in open communication with the atmosphere through the groove j^4 , the duct j^3 , the duct k^2 , the hole k^4 (in which at the time is a reduced part g' of the valve stem G), and then through the air duct k . There is also a vertical air duct k' down through the part K.

When, as stated, the float F is down, the valve f is seated, the valve g is open, and therefore the device is connected up with the air exhausting means, viz., as shown, with the inlet manifold of the motor. Therefore, the motor, on its suction strokes, withdraws air from the suction tank and from the float chamber. At this time the air inlet is closed by the valve stem G which now fills the lower end of the hole k^4 and covers the inner end of the air duct k^2 . Therefore, as air is withdrawn from the suction tank a partial vacuum therein will be produced, and this will cause the fuel to flow through the pipe R from the supply tank T into the suction tank. In the preferred construction, the parts will remain in these positions, and the device will act in the manner stated until the fuel level in the suction tank rises above the top of the float chamber. Then the fuel will rush into the float chamber, and cause the float to rise enough to lift the valve F from its seat. The fuel thereafter will not only flow over the top of the float chamber, but will also enter the float chamber through the hole d^2 with the net result that the float will very quickly rise to its highest position. This

will result in almost immediate upward movement of the float from its lowest to its highest position, and the consequent movement of the associated parts to the position shown in Fig. 1, in which the suction valve g is closed, wherefore the device is disconnected from the motor. At the same time the interior of the suction tank has been put into communication with the atmosphere, because the reduced part g' of the valve stem is now in the lower end of the hole k^4 , and opposite the inner end of the air duct k^2 . The inrushing air will very shortly restore atmospheric pressure in the suction tank and float chamber. Thereupon the valve g which is on the lower end of the discharge pipe Q secured to the bottom of the suction tank will open from the pressure of fuel against it, and said fuel will run out of the suction tank into the storage tank A. At this time also the valve f is open, and fuel will run out of the float chamber. The hole d^2 through which the fuel so flows is rather small, wherefore the suction tank will practically empty itself before enough of the fuel has run out of the float chamber to allow the float to fall. In fact, the suction pull on the seated valve g at the upper end of the valve stem G will hold the float up until the float chamber is practically empty. Then the weight of the float will overcome this suction pull, will drag the valve g from its seat, and the float will fall to the bottom of the float chamber. Thereby the parts will be restored to the position first described, as shown in Fig. 3, in which, as stated, the interior of the suction tank is no longer in communication with the air exhausting means.

In Fig. 3 a small hole d^4 is shown going through the wall of the float chamber near its lower end. If this hole is put at this place it must be so small that the fuel can not flow through it fast enough to keep the fuel level in the float chamber as high as in the suction tank. Or, in other words, the rate of flow of fuel into the float chamber must be so slow that the fuel level in the suction tank will rise more rapidly than in the float chamber. Therefore, although the float will slowly rise in the float chamber, it will not get high enough to operate the valves as stated until the suction tank is nearly full. This hole is not necessary, but if small enough is not objectionable,—but even if the hole is there, the top of the float chamber had better be open as described so that if the fuel in the suction tank rises above the top of the float chamber it may flow into the same and be sure that the float operates in time to operate the valves before any fuel can be drawn out of the suction tank through the air outlet.

It will be understood that the invention, in its broader aspects, is not dependent upon

the particular valve mechanism shown, nor on the particular arrangement of air inlet and air outlet ports.

Any suitable arrangement of air inlet ports and float controlled air exhaust ports and valves may be substituted for those shown, without departure from the invention, provided the construction and arrangement of the suction tank, float chamber and float are substantially as described so as to produce the described operation and results. The particular construction shown, however, is a good manufacturing construction for the attainment of the desired results at a minimum cost, and involves certain minor but patentable features.

Having described my invention, I claim:

1. In a vacuum feed device, the combination of a suction tank having an air outlet adapted for connection with an air exhauster, an air inlet, a liquid inlet adapted for connection with a supply tank, and a liquid outlet, a valve for said liquid outlet, a suction valve for said air outlet, which valve moves outwardly to its seat, a float chamber which communicates with the suction tank, which float chamber has also a liquid outlet in its lower end, a float in said float chamber, and means connecting said float with said suction valve.

2. In a vacuum feed device, the combination of a suction tank having an air outlet adapted for connection with an air exhauster, an air inlet, a liquid inlet adapted for connection with a supply tank, and a liquid outlet, a valve for said liquid outlet, a suction valve for said air outlet which valve moves outwardly to its seat, a float chamber which communicates with the suction tank, which float chamber has also a liquid outlet in its lower end, an outlet valve for said float chamber, a float in said float chamber, and means connecting said float with said suction valve and float chamber outlet valve.

3. In a vacuum feed device, the combination of a suction tank having an air outlet adapted for connection with an air exhauster, an air inlet, a liquid inlet adapted for connection with a supply tank, and a liquid outlet, a valve for said liquid outlet, a suction valve for said air outlet which valve moves outwardly to its seat, a float chamber which communicates with the suction tank, which float chamber has also a liquid outlet in its lower end, an outlet valve for said float chamber, an air valve for the air inlet to said suction chamber, a float in said float chamber, and means connecting said float with said suction valve, the air valve, and float chamber outlet valve.

4. In a vacuum feed device, the combination of a suction tank having an air outlet adapted for connection with an air exhauster, an air inlet, a liquid inlet adapted

for connection with a supply tank, and a liquid outlet, a valve for said liquid outlet, a suction valve for said air outlet which valve moves outwardly to its seat, a float chamber having a large liquid inlet which communicates with the suction tank at a point such that the float chamber will be suddenly flooded when the liquid level in said suction tank reaches a predetermined height, which float chamber has also a liquid outlet in its lower end, a float in said float chamber, and means connecting said float with said suction valve, and a storage tank subject always to atmospheric pressure and arranged to receive liquid discharged through the liquid outlets of the suction tank and float chamber.

5. In a vacuum feed device, the combination of a suction tank having a fuel inlet, a fuel outlet, an air inlet, and an air outlet, an open top float chamber which is fixed in said suction tank, and has a fuel outlet in its bottom, a float in said chamber having a valve for said fuel outlet on its bottom, an upwardly extended valve stem which is fixed to said float and extends upward therefrom in alignment with said air outlet from the suction tank, and has a valve formed on its upper end for closing said air outlet.

6. In a vacuum feed device, the combination of a storage tank which is always open to atmospheric pressure, an air tight suction tank within said storage tank, having an air outlet port adapted for connection with an air exhauster, an air inlet port, a fuel inlet adapted for connection with a source of fuel supply, and a fuel outlet, a valve for said outlet, an open top float chamber fixed within the storage tank having a fuel outlet in its bottom, a float in said float chamber, a valve on the bottom of said float for closing the fuel outlet, a valve stem fixed to the float and extending upward therefrom and having valves thereon for closing the air outlet and opening the air inlet when the float is in its uppermost position, and for closing the air inlet and opening the air outlet when the float is in its lowest position.

7. In a vacuum feed device, the combination of a suction tank having a fuel outlet in its bottom, a cover therefor and an open top float chamber having a fuel outlet hole through it, said cover being formed with a fuel inlet, an air inlet, and an air outlet adapted for connection with an air exhauster, a float in said float chamber, a valve stem fixed to and projecting upward from said float having a valve on its upper end for closing said air outlet, and a valve fixed to the bottom of said float for closing the fuel outlet hole in the bottom of the float chamber.

8. In a vacuum feed device, the combination of a suction tank having a fuel outlet,

an inwardly closing valve therefor, a cover removably secured to said suction tank and formed with an inwardly directed tubular member, and an open top float chamber 5 rigidly fixed to said cover, a plug closing the lower end of said tubular member, a plug closing the upper end of said member, which plugs contain vertical guide holes, a float in said float chamber, a valve stem 10 fixed to said float and extending up through said guide hole, an air outlet through said plug which is in alignment with said guide hole, and is adapted for connection with an air exhauster, an air inlet which at its inner end communicates with said guide hole, 15

said valve stem having on its upper end a valve for closing said air outlet, and having a recess in its side adjacent to said air inlet, said recess being so placed that when the air outlet valve is closed air may flow 20 into the suction tank through the air inlet and said recess in the valve stem.

In testimony whereof, I hereunto affix my signature in the presence of two witnesses.

FRIEDRICH W. BAUMGAERTNER.
